UNITED STATES PATENT OFFICE.

EDGAR H. CLARK, OF AUSTIN, ILLINOIS, ASSIGNEE, BY DIRECT AND MESNE ASSIGNMENTS, TO WESTERN ELECTRIC COMPANY, OF NEW YORK, N. Y., A CORPORATION OF ILLINOIS.

TELEPHONE SYSTEM.

1,127,405.

Specification of Letters Patent.

Patented Feb. 9, 1915.

Application filed July 3, 1912. Serial No. 707,442.

To all whom it may concern:

Be it known that I, EDGAR H. CLARK, a citizen of the United States of America, and a resident of Austin, county of Cook, and State of Illinois, have invented a new and useful Improvement in Telephone Systems, of which the following is a specification.

My invention pertains to telephone systems and its ultimate object is the economy 10 of line conductors.

It relates particularly to telephone systems wherein one or more main or central offices are supplemented by one or more out- 15 lying offices or "sub-offices," in which groups of subscribers' lines center and between which and the central office or offices trunk lines extend.

I have chosen particularly to illustrate my invention as applied to a telephone system 20 employing manually operated switchboards at its main switching center or centers, but, obviously, it may be applied to other than manual systems.

In its broad aspect my invention contem- 25 pletes the bringing of the subscribers' lines from small outlying communities of sub- 30 scribers to convenient centers remote from the central office or offices, instead of carrying them to the respective central offices 35 where they are to be switched. From each of these community centers, or sub-centers, as they may be called, I extend a group of lines, fewer in number than the subscribers' 40 lines, to the respective central office. At the central office I provide the ordinary switching mechanisms, either automatic or manual, capable of operating substantially in the same manner as if all the lines had been brought to the central office rather than to 45 the sub-offices at the sub-centers. The central office equipment is provided with the full number of jacks or other connection terminals that it would have if all the lines extended to the central office, but instead of 50 these connection terminals being extended by paths permanently connected to the corresponding lines, they are terminated in what I may term blind paths, each of which is physically dissociated from its correspond- 55 ing line, although permanently associated therewith, as by number or other designation. Likewise, each of the subscribers' lines 60 entering a sub-office terminates in a blind path physically dissociated from the corre-

sponding switchboard terminal at the cen- 55 tral office, its only association being that of number or other designation.

So far the system described is an ordinary one, with the exception that a part of each subscriber's line is lacking, each line terminat- 60 ing in a blind lead at the sub-office and its corresponding connection terminal terminat- 65 ing in a blind lead at the central office. By my invention the physical connection between the blind lead of a subscriber's line at 70 the sub-office and that of its corresponding switchboard terminal at the main office is supplied automatically, upon the initiation of a connection at either end, by any one of a group of trunk lines extending between 75 the sub-office and the main office, the number of trunks in such a group always being smaller than the number of subscribers' lines the group is intended to serve, thus result- 80 ing in the desired economy of line wires. I 75 have described such a system in my applica- 85 tion for a telephone system, Serial No. 411,669, filed January 20, 1908, and the sys- 90 tem of my present application is an improvement thereon. In that application the specific circuits and apparatus described re- 95 quired that each trunk line between the main office and the sub-office consist of three conductors. While such an arrangement re- 95 sulted in a very large economy in wire, yet it is greatly to be desired that trunks conform more nearly with standard practice to the extent of being two conductor rather than three conductor trunks. Such require- 100 ment is met by the apparatus and circuits which I describe herein. Other advantages over the system of my prior application are also to be found, such, for instance, as the greater simplicity and more direct action of the various switching mechanisms in- 105 volved.

Referring to the accompanying drawings, which illustrate and form a part of my specification—

Figure 1 is a plan view of a form of auto- 100 matic switch; Fig. 2 is a sectional view thereof, taken on the broken line A—A of Fig. 1; Fig. 3 is a diagram of a subscriber's line, the sub-office, incoming trunk line and central office circuits employed for a call 105 originating at the subscriber's station; Fig. 4 is a modification of the arrangement shown in Fig. 3; Fig. 5 is a diagram of a sub-

scriber's line, the central office, outgoing trunk line and sub-office circuits employed for completing a call to a subscriber's station; Fig. 6 is a circuit diagram of a standard manual switchboard cord circuit adaptable for use with my invention; Fig. 7 is a simplified circuit diagram, showing the arrangement for associating the trunk lines with the subscriber's lines of the group which they serve.

The automatic switch which I have shown in Figs. 1 and 2 is of a type common in the art and will be easily understood from the drawing. It is one in which a plurality of wipers 1, 2, 3, 4 and 5, rigidly mounted upon a shaft 6, journaled in housing 7, may be made to move in a circular path each over a row of contacts 21, 22, 23, 24 and 25. Rotary movement in a clockwise direction is imparted to these wipers through the ratchet wheel 8, impelled by pawl 9, and operated in an obvious manner by the electromagnet 10, which may be called the stepping magnet. The reverse or counter-clockwise movement of the wipers is produced by the coil spring 11, fixed at its inner end to the housing 7 and at its outer end to the ratchet wheel 8. This counter-clockwise movement or release is permitted by the energization of the magnet 12, which withdraws the holding pawl 13 from engagement with the teeth on wheel 8. The magnet 12 may be called the release magnet. Associated with the switch mechanism are three sets of contact springs, one of which is controlled by the stepping magnet 10; another of which is controlled by the release magnet 12, and the third of which is controlled by the rotary position of the ratchet wheel 8.

The springs of the group controlled by the magnet 10 are designated 14, 15, 16 and 17 on the drawing, and these are so arranged that each attraction of the armature of the stepping magnet will bring all of the four springs into contact with each other, each release of the armature likewise causing their separation. For purpose of greater clearness, the amount of separation of the springs 14 to 17, inclusive, each from the other, is exaggerated on Fig. 1 of the drawings, but in practice they should be so disposed with reference to the moving parts associated with the stepping magnet 10 that these springs will all be closed during that part of the movement of the armature which takes place before the wheel 8 has been moved sufficiently to cause the making and breaking among the third set of springs, 31 to 40, inclusive, which set, as stated, is controlled by the rotary position of the ratchet wheel 8.

The springs of the group under the control of the release magnet 12 I have designated as 26, 27, 28, 29 and 30. Of these, 29 and 30 are normally in engagement, but are

adapted to be broken by the attraction of the armature of magnet 12, this same movement causing the spring 30 to engage the spring 28 before breaking with springs 29. The attraction of the armature of magnet 12 also brings the springs 26 and 27 into contact.

The third group of springs, 31, 32, 33, 34, 35, 36, 37, 38, 39 and 40, forms what I term the off-normal switch, and is controlled in an obvious manner by the pin 41, mounted on the ratchet wheel 8. The movable springs 31, 34, 37 and 39 of this group change their relation with respect to the others when the wipers and ratchet wheel move from a normal to an off-normal position, or vice versa.

By normal position of the wipers I mean that position in which the wipers 1, 2, 3, 4 and 5 rest on the first contacts of their respective rows, and by off-normal position I mean any other position, this use of the terms "normal" and "off-normal" being one that is fully understood in the automatic switching art.

I have not illustrated my switch in extreme detail, as I do not desire to be limited to any particular form of switch. A large variety of switches, capable of being readily adapted to operate in connection with my system, are available and well known in the art.

I will first describe the circuit employed for connecting a calling subscriber's line to its corresponding switchboard terminal at the main office upon the origination of a call by the subscriber on that line. In Fig. 3, I show in the lower right hand corner a common battery subscriber's equipment 42, connected by the usual metallic circuit line, composed of the limbs 43 and 44, with the line apparatus at the sub-office. The automatic switch contacts which comprise the terminals of the subscriber's line are shown diagrammatically immediately above the line apparatus. Only one subscriber's line is shown, but it is to be understood that the other sets of contacts are similarly connected to subscribers' lines. The subscribers' lines are multiplied through the contacts of the other switches of the group in a manner to be hereinafter described. The apparatus associated with the sub-office end of the trunk line is shown in the lower right hand portion of the same drawing, this apparatus being connected to that at the main office by the trunk conductors 45 and 46. The apparatus associated with the main office end of the trunk line is shown in the upper right hand portion, and in the upper left hand portion is shown the main office connection terminals of the subscribers' lines. The connection terminal for this particular line is in the form of a spring jack 47, with which is associated a cut-off relay 48, a line relay 49, and a line signal 50. It must be re-

membered that normally there is no physical connection between the line of subscriber 42 and his jack 47 at the distant main office, and that the object of the automatic switching apparatus shown is to supply the gap in this subscriber's line between the sub-office and the main office as soon as the subscriber originates a call by removing his receiver from its hook. The operation to this end is as follows: The subscriber desiring a connection removes his receiver from its hook, and thus energizes the line relay 51 over the metallic circuit of his line. The operation of this relay places a ground upon the starting wire 52, which ground remains until the action of the cut-off relay 53 at the somewhat later time. At this point it may be said that the line and cut-off relays 51 and 53 are individual to the subscriber's line and that the starting wire 52 is individual to a switch, but is common to a small group, such as ten of these subscribers' lines with their corresponding lines and cut-off relays. The branches from the wire 52 represent the wires to the back contacts of each of the cut-off relays 53 belonging to the group of lines served by that wire. The grounding of the starting wire 52 permits current to pass through the stepping magnet 10 of the rotary switch, this current being periodically broken by a constantly running interrupter 54, capable of producing impulses at the required frequency for the proper operation of the switches. An impulse through the stepping magnet 10 causes the closure together of the contacts 14, 15, 16 and 17, as already described in connection with Fig. 1, and the contacts 15, 16 and 17 are thereby grounded through the contact 14.

As the first or initial operation of the stepping magnet 10 produces many changes in the circuit conditions, and as these changed conditions maintain until the switch contacts of the calling line are reached by the wipers, the circuits and apparatus will be described, first, for the initial operation of magnet 10 and then for the second and succeeding operations. The initial grounding of the contact 15 produces a circuit which, through the contacts 33 and 34 of the off-normal switch, causes the operation of the trunk cut-off relay 18. The operation of relay 18 disconnects all apparatus from the line wipers 1 and 2, thereby preventing disturbance on the contacts of the subscriber's line over which these wipers pass during the subsequent operations of the stepping magnet 10. The operation of relay 18 also disconnects the ground connection from busy test wiper 5, and disconnects the continuation of the starting wire 52¹ to prevent the starting of another trunk switch of the group, as will be hereinafter described. The grounding of contact 16

energizes relay 19, which, through its right hand contacts, switches the control of the stepping magnet 10 from the starting wire to the testing wiper 4. It also provides an alternative path through its left hand contacts for continuing the energization of relay 18, after the initial operating circuit for this relay has been broken at the contacts of the off-normal switch. 70

The grounding of the contact 17 of the stepping magnet 10 causes, through conductor 45 of the trunk and contacts 36¹ and 37¹ of the off-normal switch, the initial energization of stepping magnet 10¹ at the central office end of the trunk. The initial 80 operation of the stepping magnet 10¹ causes, through its contacts 14¹ and 15¹, the operation of the trunk cut-off relay 18¹. The operation of this relay disconnects the line wipers 1¹ and 2¹ from the rest of the apparatus, for the purpose heretofore described, and places battery through the resistance 55¹ on the trunk conductor 46 for the purpose of energizing the trunk release relay 20, when its circuit is completed at 90 the sub-office. This relay also switches the control of stepping magnet 10¹ from contacts 36¹ and 37¹, through which the initial impulse was received, directly to the trunk line conductor 45. The relay 18¹ also, 95 through its left hand contacts, dissociates the release relay 20¹ and the release magnet 12¹ from their respective wipers 3¹ and 4¹.

It will be remembered that in the description of the operation of the switch in connection with Figs. 1 and 2, the contacts of the stepping magnet were closed in advance of the changing of the relation of the contacts of the off-normal switch. 100

It will be noted from the description of 105 the circuits and apparatus given above, that alternative circuits to those originally passing through the off-normal switches have been provided for the subsequent operations of the apparatus. The relays 19 and 18¹ are 110 made of the slow-acting type by the presence of a mass of copper associated with their windings, or by any of the other well known methods, so that they will not become de-energized between the successive recurring 115 impulses supplied to them through the action of the stepping magnets 10 and 10¹, respectively. This arrangement insures that the circuits, as described above, be maintained throughout the subsequent operations 120 of the stepping magnets 10 and 10¹, or until the wipers 1, 2, 3, 4 and 5 and 1¹, 2¹, 3¹ and 4¹ rest on the sub-office terminal switch contacts and the main office terminal switch contacts, respectively, of the line of station 125 42.

Immediately following the attraction of the armature of the stepping magnets and the subsequent moving of the wipers from their normal positions, the relation of the 130

contacts of the off-normal switches is changed. Contacts 31 and 32 are closed, thereby completing the circuit from the release relay 20 to the contacts of the supervisory relay 56, and causing relay 20 to be operated. Contacts 33 and 34, which provide for the initial energization of relay 18, are broken and contact 34 is connected to contact 35, thus providing an alternative path for the operation of the relay 18, for the purpose to be hereinafter described. The starting wire 52 is disconnected from the stepping magnet 10 at the contacts 36 and 37 and is connected to a circuit which will eventually continue this wire to another trunk switch for the purpose of enabling other lines normally served by this trunk to originate calls.

The circuit between the release magnet 12 and contacts of relay 20 is completed through the contacts 39 and 40, thus providing a path for the operation of this magnet when the trunk release relay 20 is deenergized. The breaking of the connection between the contacts 36¹ and 37¹ of the off-normal switch at the central office end of the trunk broke the initial starting circuit of the stepping magnet 10¹, this magnet having been provided with an alternative path, as previously described. The closure of contacts 34¹ and 35¹ places ground upon the right hand armature of the release relay 20¹, this being for the purpose of later providing a locking circuit for relay 20¹. Contacts 31¹ and 32¹ complete a circuit to the release magnet 12¹, which provides means for subsequently releasing the switch at the proper time.

In the circuits, as described above, provision has been made for the continued operations of the stepping magnet 10, and the simultaneous operations of the stepping magnet 10¹, as the wiper 4 passes over the contacts 24¹, 24², etc., of the lines associated with this switch. Through the operation of the off-normal switches, preliminary circuits have been established for the subsequent release of the apparatus when a connection is no longer desired.

As has been previously described, the control circuit for the stepping magnet 10, after the initial operation of this magnet, is connected to wiper 4. It will be noted that as long as the wiper 4 encounters a ground connection on the contacts 24¹, 24², etc., over which it passes, a circuit will be provided for the operation of magnet 10. The contacts 24¹, 24², etc., will be grounded in all cases except that of the line on which the receiver is removed from the hook switch and which has not as yet been connected with its respective central office terminal; or, in other words, ground will appear upon these contacts of all the lines on which the relay 51 is deenergized. This relay will be deenergized

on all lines which are idle, or which are actually engaged in a connection. Therefore, assuming station 42 to be calling, when the wipers of the switch are stepped to contacts 21¹, 22¹, 23¹, 24¹ and 25¹, ground will be encountered on contact 24¹, and the switch wipers will be moved to the next position, or that of the line which we have assumed as desiring to originate a call. On this line the contact 24² will be disconnected from the ground, inasmuch as the removal of the hook switch at the station 42 caused the energization of the relay 51, and as cut-off relay 53 has not as yet been energized, relay 51 is still in an energized condition. As previously described stepping magnet 10¹ is made to operate simultaneously with the operation of stepping magnet 10. Therefore, the wipers of the central office end of this trunk line will have been moved to the contacts 71², 72², 73² and 74², or the central office terminals of the line 42. The stepping magnet 10 will now cease to be energized and the slow-acting relays 18¹ and 19, which have been maintaining the circuit conditions since the initial impulse, will also become deenergized. The deenergization of relay 19 will, through its left hand contacts and the contacts of the release relay 20, which relay has previously been energized, establish a circuit through the wiper 3 for the operation of the cut-off relay 53, thereby disabling the line relay 51 and establishing ground on the contacts 24² of the other switches through which this line is multiplied. These same contacts of relay 19 also establish a preliminary circuit for the subsequent release of the switch. The deenergization of relay 18 connects the contacts 21² and 22² of the line of station 42, through the wipers 1 and 2, with the repeating coil and supervisory relay, thereby producing a circuit over which conversation may take place and over which supervisory signals may be passed. The release of relay 18 also places ground, through wiper 5, upon the contact 25², this being for the purpose of establishing a busy condition for incoming calls to this line. Starting wire 52, which, as before described, serves a group of lines, is continued through contacts of the off-normal switch and contacts of the relay 18 to wire 52¹, associated with another switch serving the same group of subscribers. The release of relay 18¹ has connected the trunk conductors 45 and 46 to the contacts 71² and 72², respectively, which contacts are the central office terminals associated with station 42. The closure of the left hand contacts of this relay has established the preliminary circuit for the release.

The complete circuit involved in the subscriber's line is as follows: from ground, through winding of relay 56, repeating coil 68, contacts of relay 18, wiper 1, switch contact 21², conductor 43, through station 42, 130

conductor 44, switch contact 22², wiper 2, contacts of relay 18, winding of repeating coil 68, winding of relay 56, to battery. The supervisory relay 56 is now placed in the battery feed circuit of station 42, and will be energized or deenergized according to the position of the hook switch at that station. The trunk line circuit, and the circuit at the central office associated therewith, is as follows: from battery to winding of relay 49, contacts of relay 48, switch contact 72², wiper 2¹, conductor 46, winding of relay 20, contacts 31 and 32 of off-normal switch, contacts of relay 56 (it being assumed that the receiver is off the hook at station 42), winding of repeating coil 68, trunk line conductor 45, contacts of relay 18¹, wiper 1¹, switch contacts 71², contacts of relay 48 to ground. It will be noted that this circuit has included in it the winding of the relay 49, which relay will be energized and cause the illumination of the line signal 50. The line of station 42 is now connected, through a repeating coil, with its corresponding central office terminal, and the line lamp has been illuminated, indicating that a connection is desired.

The operator answers the calling subscriber by inserting the answering plug 57 (Fig. 6) in the jack 47 (Fig. 3) and thus, as in the usual manual multiple switchboard practice, furnishes current for the operation of cut-off relay 48, which in turn extinguishes the line lamp by deenergizing the line relay 49. The operation of the cut-off relay 48 changes the battery supply from the path through the line relay 49 to the cord circuit, battery and ground connection now being made to the two limbs of the trunk line through the two supervisory relays 59 and 58, respectively.

The circuits of my invention are adapted to provide the customary signaling or supervisory means between the subscriber's station and the central office. The supervisory lamp 60 (Fig. 6) is controlled by the two supervisory relays 58 and 59, the lamp being extinguished when a conducting path across the two limbs of the line causes the energization of both relays 58 and 59, and being lighted when relay 59 is energized and relay 58 deenergized as a result of the grounding of the continuation of the sleeve side of the cord circuit and the opening of the continuation of the tip side of the cord circuit.

The supervisory relay 56 (Fig. 3), which has previously been described as being controlled in its operation by the hook switch at station 42, controls the relay 58 (Fig. 6), and this in turn controls the supervisory lamp 60. The circuit including relay 58 is as follows: from ground to winding of relay 58, tip of plug 57, tip of jack 47, contacts of relay 48 (Fig. 3), switch contact 71²,

wiper 1¹, contacts of relay 18¹, trunk conductor 45, winding of repeating coil 68, contacts of relay 56, contacts 32 and 31 of off-normal switch, winding of relay 20, winding of repeating coil 68, trunk conductor 46, contacts of relay 18¹, wiper 2¹, switch contact 72², contacts of relay 48, sleeve of jack 47, sleeve of plug 57, relay 59 to battery. It will be seen, therefore, that relay 58 and supervisory lamp 60 are controlled by relay 56, which relay is in turn controlled by the hook switch at the calling station. In order to prevent relay 20 from being released when relay 56 is deenergized, thereby releasing the switch, relay 56 is of the make before break type and thus provides an alternate circuit which insures the continued energization of relay 20, regardless of the position of the armature of relay 56. This alternate circuit is as follows, it being remembered that trunk conductor 46 is connected to battery through the cord circuit: from trunk conductor 46 to winding of repeating coil 68, winding of relay 20, contacts of off-normal switch, contacts of relay 56 to ground.

The release of the trunk line and its associated switches, at the end of a conversation or when the connection is no longer wanted between the main office and sub-office terminals of the subscriber's line, is controlled by the operator and is accomplished by the withdrawal of the answering plug from the jack. The main office switch is restored first and when this switch is at its normal position, the switch at the sub-office is restored.

The insertion of the operator's plug into the jack and the operation of the cut-off relay established the connection for energizing the release relay 20¹, which circuit may be traced from battery, through the coil and contacts of relay 20¹, contacts of relay 18¹, wiper 3¹, switch contact 73², contacts of relay 48 to ground. The attraction of the right hand armature of the relay 20¹ established a local locking path from battery, through the winding and contacts of the relay, contacts 34¹ and 35¹ of the off-normal switch to ground, the switch being at that time in its off-normal position. As a result, relay 20¹ being once pulled up remains so until the switch again returns to its normal position. When relay 48 is released by the removal of the plug 57 from the jack 47, ground is placed on the switch contact 74². This ground completes the path for the energization of the release magnet 12¹ as follows: from ground to contacts of relay 48, switch contact 74², wiper 4¹, contacts of relay 18¹, contacts of relay 20¹, contacts of magnet 12¹, contacts of off-normal switch, winding of magnet 12¹ to battery. The contacts of the magnet 12¹, over which this circuit passes, are of the make before break type and, when this magnet is oper-

ated, produce a locking circuit which continues the energization of this magnet until the switch wipers rest on their normal contacts. Relay 18¹ is operated through a circuit established by the left hand contacts of relay 12¹. The operation of relay 18¹ disconnects the wipers 1¹ and 2¹ from the rest of the apparatus, and thereby permits them to pass over the switch contacts without interfering with the lines connected thereto. It will be remembered that a battery connection has been maintained with trunk line conductor 46 for the purpose of energizing trunk release relay 20. The operation of relay 18¹ places battery, through a resistance 55¹, on the above mentioned trunk conductor, thus causing relay 20 to continue in an operated position until the relay 18¹ is released, when the switch with which it is associated reaches its normal position. When relay 20 is deenergized, a circuit is established for the operation of magnet 12. This magnet is of the locking type as before described, and after having once been energized, remains in an energized position until the wipers of this switch rest in their normal position. Relay 12 also operates cut-off relay 18 for the purpose of isolating the line wipers of the switch during their return to normal position. The main office and sub-office terminals of the subscribers' lines have now been physically dissociated and the trunk line and its associated apparatus is in its normal position.

35 In order to prevent a trunk line and its associated apparatus from becoming inoperative, due to the starting of a switch by a momentary ground on conductor 44 or by an accidental movement of the armature of relay 51 or magnet 10, provision is made for automatically releasing the switches when the wipers have passed over the switch contacts and have failed to find a line calling. This automatic release is provided for by 40 the row of contacts 71⁵, 72⁵, 73⁵, 74⁵ placed immediately beyond the last line contacts of the switch. The lower two contacts of the groups 73⁵ and 74⁵ are connected to ground, and when the wipers 3¹ and 4¹ rest on this 45 contact a release circuit is established similar to that heretofore described.

I will now describe the circuit and apparatus employed in connecting a switchboard terminal at the main office with its corresponding subscriber's line and terminal at the sub-office, this circuit being the one employed in completing the connection with a called subscriber's line.

The operator, after having learned the 50 number of the subscriber to be called, tests a multiple jack of that line in the usual manner to determine whether or not the subscriber's line is already connected with at some other point in the multiple. If the 55 multiple associated with the line is found

idle, the operator inserts the calling plug of a cord pair in the multiple switchboard jack and rings the subscriber in the usual manner. The act of inserting the plug of the cord pair in the multiple jack causes the switch associated with a trunk to seek, find and connect the subscriber's jack with that trunk at the main office, and causes the switch associated with that trunk at the sub-office to connect with the switch terminals of the corresponding line. If the line called is in use for an originating call from that station, the trunk switch wipers at the sub-office will, after testing the switch contacts, return to their normal position and place a busy tone on the trunk line, and thereby provide a busy back signal for the operator. The circuits employed in the selection of the outgoing trunk and its associated switches and the connection with the subscriber's line at the sub-office are as follows: The insertion of the plug in the multiple jack causes the relay 61 (Fig. 5), associated with that line, to be energized by a circuit as follows: from battery associated with the cord circuit (Fig. 6) to relay 59¹, contacts of key 64, sleeve of plug 57¹, sleeve of jack 63 (Fig. 5), winding of relay 61, thence to ground. The operation of relay 61 places ground on the common starting wire 52², which causes the switch of an idle, trunk to seek, find and connect with the switch terminals of that line at the main office, and simultaneously cause the switch at the sub-office end of the trunk to connect 100 with the switch terminals of the corresponding line. The circuit established for the purpose of giving the initial or starting impulse to the stepping magnet of the trunk switch is as follows: from ground to contacts of relay 61, contacts of relay 62, starting wire 52², contacts 37², 36² of the off-normal switch, winding of stepping magnet 10², thence to and through the interrupter 54² to battery. This circuit includes the winding 105 of relay 10² and will cause it to be energized.

As the first or initial operation of the stepping magnet 10² produces many changes in the circuit conditions, and as these 110 changed conditions maintain until the switch contacts of the calling line are reached by the wipers, the circuits and apparatus will be described, first, for the initial operation of the magnet 10² and then for the second and succeeding operations.

The initial grounding of the contact 15² produces a circuit which, through the contacts 33² and 34² of the off-normal switch, causes the operation of the trunk cut-off relay 18². The operation of relay 18² disconnects all the apparatus from the line wipers 1² and 2², thereby preventing disturbance on the contacts of the subscribers' lines over which these wipers pass during the subsequent operations of the stepping magnet 10².

The operation of relay 18² also connects battery through resistance 55² to the trunk conductor 46¹, to replace the battery connection which, up to this time, was supplied through the cord circuit. Relay 18² also disconnects the continuation of the starting wire 52² to prevent the starting of another trunk switch of a group, as will be hereinafter described. The grounding of contact 16² energizes relay 19², which, by means of one of its lower set of contacts and contacts of the off-normal switch, switches the control of the stepping magnet 10² from the starting wire to the testing wiper 4². It also provides an alternative path through its upper set of contacts for continuing the energization of relay 18² after the initial operating circuit for this relay has been broken at the contacts of the off-normal switch. The grounding of contact 17² of stepping magnet 10² causes, through trunk conductor 45¹ and contacts 37² and 36² of the off-normal switch, the initial energization of the stepping magnet 10² at the sub-office end of the trunk. The initial operation of the stepping magnet 10² causes, through its contacts 14² and 15², the operation of the trunk cut-off relay 18³. The operation of this relay disconnects the line wipers 1² and 2² from the rest of the apparatus for the purpose heretofore described, and switches the control of the stepping magnet 10² from contacts 36² and 37² of the off-normal switch, through which the initial impulse was received, to contacts of relay 67, and thence to the trunk line conductor 45¹. This relay also provides a circuit for continuing the energization of relay 67. Magnet 10², through contacts 14² and 17² provides a path for the initial energization of the relay 67. This relay is connected through the winding of the repeating coil 68³ to the trunk conductor 46¹, which has previously been described as being connected to battery through resistance at the central office.

It will be remembered that in the description of the operation of the switch in connection with Figs. 1 and 2, the contacts of the stepping magnet were closed in advance of the changing of the relation of the contacts of the off-normal switch. It will be noted from the description of the circuits and apparatus given above that alternative circuits to those originally passing through the off-normal switches have been provided for the subsequent operations of the apparatus. The relays 18² and 19² at the central office and 18³ and 20³ at the sub-office are made of the slow-acting type, so that they will not become deenergized during the subsequent momentary breaking of their controlling circuits.

Immediately following the attraction of the armatures of the stepping magnets and the subsequent moving of the wipers from

their normal positions, the relation of the contacts of the off-normal switches is changed. Contacts 33² and 34² are broken, the circuit of relay 18², which originally passed through these contacts, having been transferred to contacts of relay 19². The starting wire 52² is disconnected from the stepping magnet 10² at the contacts 36² and 37², and is connected through contacts 37² and 38² to a circuit which will eventually continue this wire to another switch for the purpose of enabling other lines, normally served by this trunk, to originate calls. The circuit between the release magnet 12² and contacts of the relay 19² is completed through the contacts 39² and 40², thus providing a path for the operation of this magnet when disconnection is desired. The breaking of the connection between the contacts 36² and 37² of the off-normal switch at the sub-office end of the trunk broke the initial controlling circuit of the stepping magnet 10², this magnet having been provided with an alternative path, as previously described. The circuit between the release magnet 12² and contacts of relay 20³ is completed through the contacts 39³ and 40³, thus providing a path for the operation of this magnet when the trunk release relay 20³ is deenergized.

In the circuits as described above, provision has been made for the continued operation of the stepping magnet 10² and the simultaneous operation of the stepping magnet 10² as the wiper 4² passes over the contacts 88¹, 88², 88³, etc., of the lines associated with this switch. Through the operation of the off-normal switches, preliminary circuits have been established for the subsequent release of the apparatus when a connection is no longer desired.

As has been previously described, the control circuit of the stepping magnet 10² by the initial operation of this magnet is connected to wiper 4². It will be noted that as long as wiper 4² encounters a ground connection on the various contacts 88¹, 88², etc., over which it passes, a circuit will be provided for the operation of magnet 10². The contacts 88¹, 88², etc., will be connected to ground in all cases except that of the line of which a plug has been inserted in the multiple jack, and which has not as yet been connected with its respective subscriber's line, or, in other words, ground will appear upon those contacts of all the lines on which relay 61 is deenergized. Also when a subscriber's terminal is connected with by one of the other switches of a group, ground is placed upon the multiple of this contact in each of the switches, thereby causing the wipers of the seeking switch to pass over the switch contacts of the connected lines. It will be noted that the contact 88¹ is connected directly to ground, thereby insuring

that the wipers will always pass over this set of contacts, which is provided for a purpose to be hereinafter described. Therefore, assuming that connection is desired with station 42³, which station is represented at the central office by multiple jacks 63, 63¹, etc., and switch contacts 85³, 86³, 87³, 88³ and 89³, then when the wipers of the switch are stepped to the set of contacts 85¹, 86¹, etc., 10 and likewise to the set of contacts 85², 86², etc., ground will be encountered on the contacts 88¹ and 88² of these sets, and the switch wipers will be moved in each case to the next position, or finally to the contacts 85³, 86³, 15 etc., which represent the line with which we have assumed a connection is desired. Contact 88³ of this group will be disconnected from ground, inasmuch as relay 61 is energized through the presence of a plug in the 20 switchboard jack 63, relay 62 not as yet being energized, and consequently the wipers 1², 2², etc., will remain on the switch contacts associated with this line. As previously described, stepping magnet 10³ is made 25 to operate simultaneously with the operation of stepping magnet 10². Therefore, the wipers of the sub-office end of the trunk switch will have been moved to the contacts 80³, 81³, 82³, etc., or, in other words, to the 30 switch contacts of the line of station 42³. If the station of this line is not engaged in an originating calling, the slow-acting relays, which have been maintaining the circuit conditions since the initial impulse, will 35 become deenergized and the wipers of the switches associated with this trunk will remain on this set of sub-office switch contacts. Relay 19² will, through its upper set of contacts, establish a circuit through the wiper 4² 40 for the operation of relay 62, thereby disconnecting the common starting wire 52² from this line. Through one of the lower sets of contacts of relay 19² ground will be placed on the wiper 4² and contact 88³ for 45 the purpose of causing wipers of other switches to pass over the multiple contacts of this line. Through the other lower set of contacts of this relay a circuit is established which will ultimately serve a portion of the 50 release circuit when relay 61 is deenergized on the removal of the plug from the switchboard jack. The deenergization of relay 18² connects the line contacts 85³ and 86³, 55 through the wipers 1² and 2², to the trunk conductors 45¹ and 46¹, respectively, thereby producing a circuit over which conversation 60 may take place and over which ringing and supervisory signals may be passed. The starting wire 52², which as before described, 65 serves a group of lines, is connected through the contacts of the off-normal switch and contacts of the relay 18² to wire 52³ associated with another switch serving the same group of subscribers. At the sub-office the 70 deenergization of the relay 18² connects the

subscriber's line with the windings of repeating coil 68³ through the wipers 1³ and 2³ and switch contacts 80³ and 81³, respectively. This relay also provides a path for the operation of cut-off relay 53³. Relay 67 70 is now deenergized and connects battery, through the supervisory relay 56³, to one winding of the repeating coil 68³. The corresponding winding of the repeating coil 68³ 75 is already connected through the resistance 56⁴ to ground, so that this deenergizing of the relay 67 results in establishing a complete supervisory and talking circuit for the subscriber's station. The subscriber's line is now connected through repeating coils to its 80 associated central office jack, and the operator may ring the subscriber in the usual manner.

The cord circuit, shown in Fig. 6, is of the type in which a battery, through resistance is connected to the sleeve of the plug during the ringing period, thereby insuring that relay 61 and trunk release relay 20² 85 will remain energized. Relay 67 at the sub-office end of the trunk is of a type which will readily respond to ringing current and will thereby connect the trunk conductor 45¹ through the switch apparatus to the limb 43³ of the subscriber's line, thereby eliminating the necessity of ringing through the repeating coil. This circuit of my invention is adapted to provide the customary signaling or supervisory means between the subscriber's station and the central office in a manner similar to that provided in the circuits shown in Fig. 3, and therefore in view of the previous description, will be readily understood from the drawing. The means for insuring the continued energization of the release relay 20² is also similar to that 95 already described.

It was assumed that the station with which connection was desired was not engaged in an originating call. If this station had been so engaged, provisions are 100 made for notifying the operator of that fact. It will be remembered that in connection with Fig. 3 a ground connection was placed on switch contact 25² when that line was connected with the central office. These 105 contacts, as well as all the contacts of a set, are multiplied through the switches associated with both incoming and outgoing trunks, serving the same group of subscribers at the sub-office. Therefore, when the 110 line is busy in connection with an originating call, this corresponding contact in each of the switches is connected to ground. Consequently, when a switch at the sub-office 115 associated with an outgoing trunk from the 120 main office attempts to connect with a busy line, ground is connected to the wiper 4³, and through the contacts of the cut-off relay 18³ a circuit is established which causes the 125 energization of the release relay 12³, thereby 130

restoring the wipers of this switch to their normal position. When the off-normal switch changes the relation of its contacts, which occurs as the wipers return to normal position, a circuit is provided from battery, through the winding of the stepping magnet 10³, contacts 36³ and 37³ of the off-normal switch, winding of repeating coil 68³, conductor 45¹, contacts of relay 18², wiper 1², switch contact 85³ to tip of multiple jack 63, tip of plug 57¹, thence to ground through the supervisory relay 58¹. This circuit will cause stepping magnet 10³ to move the wipers from their normal position to the contacts 80¹, 81¹, etc., and as the circuit which caused this movement will then be broken at the off-normal switch, the wipers will remain in that position. Connected with the switch contacts 80¹ and 81¹ is the busy back signal commonly employed in switchboard practice. Through the wipers of this switch, the repeating coil and conductors of the trunk line, the busy tone will be placed upon the operator's cord circuit. The operator, after having received the notification of the busy condition, will restore the apparatus to normal as hereinafter described.

The release of the trunk line and its associated switches at the end of the conversation, or when connection is no longer wanted between the main office and the sub-office terminals of the subscriber's line, is controlled by the operator, and is accomplished by the withdrawal of the calling plug from the multiple jack. The main office switch is restored first, and when this switch is at its normal position the switch at the sub-office is restored. Certain preliminary release circuits, as heretofore described, have been established. When the operator removes the plug from jack 63, relay 61 is de-energized and ground is placed on the switch contact 89³. The ground completes the circuit through contacts of the relay 19² and the off-normal switch thus operating relay 12². Relay 12² is of the locking type, as previously described, and will remain in an energized position until the switch wipers reach their normal contacts. The operation of relay 12² causes the operation of relay 18², which relay continues the energization of the trunk release relay 20³ until the trunk switch at the central office has returned to its normal position. When relay 20³ is de-energized a circuit is provided for the energization of relay 12³. This relay is of the locking type and will remain in its energized position until the switch wipers are returned to normal. Through the contacts of relay 12³ a circuit is provided for the energization of relay 18³, this being for the purpose heretofore described. The main office and sub-office terminals of the subscribers' lines have now been physically

dissociated and the trunk line and its associated apparatus is in its normal position.

In order to prevent a trunk line and its associated apparatus from becoming inoperative, due to the starting of a switch by an accidental momentary operation of the armature of relay 61, provision is made for automatically releasing the switch when the wipers have passed over the switch contacts and have failed to find a switchboard terminal with which connection is desired with its associated subscriber's line. This automatic release is provided by a row of contacts 85⁶, 86⁶, 87⁶, etc., placed immediately beyond the last line contacts of the switch. The lower contact of this group 89⁶ is connected to ground, and when wiper 5² rests on this contact a release circuit is established similar to that heretofore described.

In Fig. 4 I show a modified form of circuit for incoming calls to the central office, whereby, in addition to the saving in line conductors, I effect a saving in apparatus as compared with the circuit for incoming calls as shown in Fig. 3. In this modification, instead of representing each subscriber's line in an answering jack at the central office, the trunk lines themselves terminate in answering jacks, thereby eliminating the necessity of providing switches on the central office ends of the incoming trunks. All the advantages of the other arrangement are retained except that the operator must learn the number or designation of the calling subscriber by inquiring instead of by a visual inspection when such information is desired or necessary. In this circuit the subscriber's line, line apparatus and switch terminals are similar to those shown in Fig. 3. The operation of the various elements of the trunk switch is also similar. The stepping magnet 10⁴ is initially started over the starting wire 52⁴, its subsequent control being through the testing wiper 4⁴. The relays 18⁴ and 19⁴ are operated by the initial operation of the armature of the magnet 10⁴. These relays are, as before, of the slow-acting type. The release relay 12⁴ is controlled through the off-normal switch and contacts of the release relay 20⁴. The circuits for the operation of these various relays and magnets are self-evident by an inspection of the drawing, in view of the description already given in connection with the other circuits. The central office apparatus is somewhat different from that employed in Fig. 3, in that the trunk switch and its associated apparatus is omitted entirely. The answering jack is of the cut-off type, thereby making the use of a cut-off relay unnecessary. The description of the circuit, in so far as it differs from those already described, will now be given.

The operation of relay 19⁴ completes a circuit which provides for the initial ener-

gization of the trunk release relay 20⁴. This circuit may be traced as follows: from battery to contacts of relay 19⁴, winding of relay 20⁴, contacts of supervisory relay 56⁴ to ground. When relay 18⁴ operates it provides, through a lower set of contacts, a circuit which includes a winding of supervisory relay 56⁴, and causes the latter to operate. The energization of relay 56⁴ completes a circuit for the operation of the line relay 49⁴ and the continued energization of relay 20⁴, as follows: from ground to winding of relay 49⁴, contacts of jack 65, trunk conductor 46⁴, winding of repeating coil 68⁴, contacts of relay 56⁴, winding of relay 20⁴, contacts of relay 19⁴ to battery. The operation of relay 49⁴ causes the illumination of the line lamp 50⁴ and provides a circuit for continuing the energization of relay 20⁴ after relay 19⁴ has been released. This latter circuit is as follows: from battery to resistance 66, contacts of relay 49⁴, contacts of jack 65, trunk conductor 45⁴, repeating coil 68⁴, winding of relay 20⁴, contacts of relay 56⁴, repeating coil 68⁴, trunk conductor 46⁴, contacts of jack 65, winding of relay 49⁴ to ground. The operator answers the call and completes the connection in the usual manner. The cord circuit as well as the supervisory and release circuits are evident from the drawing in view of the description of the corresponding circuits in connection with Fig. 3.

In the description of the circuits of my invention I have made reference to the means provided for extending the starting wire of a switch to another switch serving the same group of subscribers when that switch becomes engaged in a connection. This provision is for the purpose of enabling any subscriber of a group to obtain connection as long as any trunk associated with that group is idle. I have shown in Fig. 7 a simplified circuit embodying the elements involved in the selection of a trunk switch. In order to simplify the description, I will assume that a group of ten trunk switches serve 100 subscribers. The switch contacts of each switch will, therefore, represent 100 lines. In the drawing, the wire 90¹ and its ten branches represent the starting wire and the connection to each of the lines of the first ten subscribers of the hundred respectively. The starting wire 90² and its branches are similarly associated with the second set of ten lines, and the starting wire 90¹⁰ is associated with the last or tenth group of ten lines. 91¹ represents the stepping magnet and its contacts involved in the starting circuits. 92¹ represents the trunk cut-off relay, and 93¹ represents the off-normal switch. These parts are similarly shown for the second, and also the tenth switch. It will be remembered in the previous description that 65 the starting wire was disconnected from the

stepping magnet, immediately after the initial impulse, by the off-normal switch, and at the off-normal switch connected to contacts of the trunk cut-off relay, which latter relay on its release serves to continue the starting wire to another switch. These circuits are shown in Fig. 7 and are as follows: Starting wire 90¹ provides a circuit for the initial operation of the stepping magnet 91¹. Immediately after the attraction of the armature of this magnet, the circuit is broken at the off-normal switch 93¹ and connected to a wire leading to a contact of the cut-off relay 92¹. This circuit is open at this point, due to the energization of relay 92¹ by the stepping magnet 91¹. When the stepping magnet 91¹ ceases to operate, the relay 92¹ is deenergized and the starting wire 90¹ is connected through contacts of this relay to the starting wire 90², which serves the second set of ten lines, and is normally connected to the second switch. The circuit arrangement is similar for the second switch and the other switches of the group. The starting wire 90¹⁰ of the tenth switch, when this switch is in use, is connected to the starting wire 90¹ of the first switch.

In the circuits as just described, it will be readily seen that when a subscriber of the first group of ten lines has appropriated the first switch or that normally associated with that group, the starting wire is connected to the starting wire of the second group, so that should a second subscriber of the first group of ten lines desire a connection he will have placed at his disposal the second switch. When all the switches are in use, the starting wires serving all the subscribers' lines are connected together, and the next subscriber desiring a connection will, when one of the trunk lines becomes free, have at his disposal this trunk line regardless of the group in which his line is found and the group which this switch normally serves.

The order in which the subscribers' lines are multiplied through the contacts of the trunk switches differs in each switch. This arrangement of the relation of the lines with respect to the multiple is for the purpose of normally permitting the connection to be established with the fewest possible steps of the wipers of a switch. The arrangement is, that in the first switch the first ten subscribers' lines will be connected to the first ten sets of contacts. In the second switch the second set of ten subscribers' lines will be connected to the first ten sets of contacts, and so on, the lines normally served by a switch always being connected to the first set of ten contacts. In each case, the other groups of subscribers' lines are so associated with the multiple switch contacts that normally a particular switch will be required to pass over the entire contacts only when all the trunks except one have been engaged.

The contacts of the switches on the two ends of a trunk line must of course be connected in the same order. I will describe in detail the arrangement of all the subscribers' lines with respect to the first switch, in order to illustrate this point more clearly. As before stated, the first group of ten subscribers' lines will be connected to the first set of ten contacts. The tenth group of subscribers' lines will be connected to the second set of ten contacts; the ninth to the third; the eighth to the fourth; the seventh to the fifth; the sixth to the sixth; the fifth to the seventh; the fourth to the eighth; the third to the ninth and the second to the tenth. It is obvious that the subscribers' lines may be divided into groups having a greater or less number than one hundred served by a particular group of trunks.

In the figures illustrating the circuit arrangement of my invention I have in each case shown only one trunk line, one subscriber's line and the multiple switch contacts for four subscribers' lines. However, I do not wish to limit my invention in this respect, as it is obvious that the number of such lines may be increased without departing from the spirit of my invention.

While I have illustrated and described certain forms of my invention, it is understood that numerous changes may be made therein without departing from the spirit or narrowing the scope of my invention.

Having thus described my invention, what I claim as new and desire to secure by United States Letters Patent is:

1. In a telephone system, a two-wire trunk line adapted to form a talking circuit between two points; two selecting switches, one for each end of said trunk line; electromagnetic means for automatically moving said switches in unison to establish a talking connection over said trunk, and means for releasing said switches, the control between said switches for both connecting and releasing being over the two wires of said trunk.

2. In a telephone system, a trunk line adapted to form a link in a talking circuit; two selecting switches, one at each end of said trunk line; means for automatically moving said two switches in unison to extend the two ends of said trunk line; and means for releasing said switches, the control between said switches for both connecting and releasing being over the talking wires of said trunk.

3. In a telephone system, a central office and a sub-office; a trunk line adapted to form a talking circuit between said offices; a selecting switch for said trunk line at each of said offices; means for automatically moving said two switches in unison to extend the two ends of said trunk upon the initiation of a connection at one of said offices, and means

for returning the switches to their normal positions at the end of a conversation, the control of said switches between said offices being over the talking wires of said trunk.

4. In a telephone system, a switchboard having a plurality of subscribers' line terminals; a plurality of subscribers' lines dissociated from said switchboard line terminals and pertaining respectively to each of said switchboard terminals; a two-wire trunk common to all said subscribers' lines; a switch for each end of said trunk; means for causing said switches automatically to connect one of said subscribers' lines to its corresponding switchboard terminal when a call is initiated on said line; and means for releasing said switches, the distant control of said switches for both connecting and releasing being over the two conductors of said trunk.

5. In a telephone system, a switchboard having a plurality of subscribers' line terminals; a plurality of subscribers' lines dissociated from said switchboard and pertaining respectively to each of said line terminals, a two-wire trunk common to all said subscribers' lines; a switch for each end of said trunk; means for causing said switches automatically to connect one of said terminals to its corresponding subscriber's line when a connection is initiated with said switchboard terminal, and means for releasing said switches, the distant control of said switches for both connection and releasing being over the two conductors of said trunk.

6. In a telephone system, a group of subscribers' lines; a switchboard having a group of line terminals normally dissociated from said lines; a trunk common to the lines and terminals of said respective groups and adapted to form a link in a talking circuit between any subscriber's line and its corresponding switchboard terminal; switches at each end of said trunk acting automatically to connect a subscriber's line with its corresponding switchboard terminal upon the initiation of a call on said line, and means for releasing said switches, the distant control between said switches in connecting and releasing being over the talking conductors of said trunk.

7. In a telephone system, a switchboard having a plurality of subscribers' line terminals; a plurality of subscribers' lines dissociated from said switchboard and pertaining respectively to each of said line terminals, a trunk common to said lines and terminals and adapted to form a link in a talking circuit between any subscriber's line and its corresponding switchboard terminal; a switch for each end of said trunk; means for causing said switches automatically to connect one of said terminals to its corresponding subscriber's line when a connection is initiated with said switchboard terminal;

and means for releasing said switches, the means for releasing one of said switches being controlled over one of the talking wires of said trunk.

5. 8. In a telephone system, a switchboard having a plurality of subscribers' line terminals; a plurality of subscribers' lines dissociated from said switchboard and pertaining respectively to each of said line terminals; a trunk common to said subscribers' lines and terminals and adapted to form a link in a talking circuit between any subscriber's line and its corresponding terminal; a switch for each end of said trunk; 10 means for causing said switches automatically to connect one of said terminals to its corresponding subscriber's line when an outgoing connection is initiated at said switchboard terminal; and means for releasing said 15 switches, the means for releasing the switch at the subscriber's line end of said trunk being controlled over one of the talking conductors of said trunk.

9. In a telephone system, a two-wire trunk line adapted to form a link in a talking circuit; two selecting switches, one at each end of said trunk line; means controlled over one side of the talking circuit of said trunk for automatically moving said two switches 25 in unison to extend the two ends of said trunk line; and means for releasing said switches, the release means for one of said switches being controlled over the other side of the talking circuit of said trunk.

- 30 10. In a telephone system, a two-wire trunk line adapted to form a link in a talking circuit; an automatic selecting switch at each end of said trunk line; a group of paths terminating in each of said switches; means 35 for automatically moving said two switches in unison to connect the two ends of said trunk line to corresponding ones of said paths, said means being controlled over one side of the talking circuit of said trunk, and 40 means for restoring said switches, said restoring means being operated over the other side of the talking circuit of said trunk.

11. In a telephone system, a central office and a sub-office; a group of subscribers' lines 45 terminating at said sub-office; a trunk common to said group of subscribers' lines adapted to form a talking circuit between said offices; a switch for said trunk at said sub-office adapted to automatically establish 50 a connection between one of said lines and said trunk upon the initiation of a call on said line; and means for releasing the switch of said trunk, said means being controlled over one of the talking wires of said trunk.

- 60 12. In a telephone system, a switchboard having a plurality of subscribers' line equipments; a plurality of subscribers' lines dissociated from said switchboard and pertaining one to each of said line equipments; an

automatic switch for selecting and connecting with said subscribers' lines; an automatic switch for selecting and connecting with said subscribers' line equipments of said switchboard; a two-wire trunk line connecting said switches; means controlled over 65 said trunk line for causing said two automatic switches to move in corresponding steps during selection; and means for restoring said two automatic switches, the restoration of one of said switches being controlled 70 over one of the two wires of said trunk line.

13. In a telephone system, a central office and a sub-office; a group of subscribers' lines terminating at said sub-office; a switchboard having a plurality of subscribers' line terminals at said central office; a plurality of trunk lines, less in number than the subscribers' lines or corresponding switchboard terminals, said trunk lines being adapted to 75 form connecting links in the talking circuits between the subscribers' lines and the central office; a selecting switch at each end of each trunk line; means for appropriating an idle one of said trunk lines upon the initiation of a call on a subscriber's line; means 80 for causing the switches of the trunk line so appropriated to connect at one end with the subscriber's line and at the other end with the corresponding switchboard terminal; and means for causing the release of 85 said switches, the control between said switches for both selecting and releasing being over the talking circuit wires of said trunk line.

14. In a telephone system, a central office and a sub-office; a group of subscribers' lines terminating at said sub-office; a switchboard having a plurality of subscribers' line terminals at said central office; a plurality of trunk lines, less in number than the subscribers' lines or corresponding switchboard terminals, said trunk lines being adapted to 90 form connecting links in the talking circuits between the subscribers' lines and the central office; a selecting switch at each end of each trunk line; means for appropriating an idle one of said trunk lines upon the initiation of a call on a subscriber's line; means for 95 causing the switches of the trunk line so appropriated to connect at one end with the subscriber's line and at the other end with the corresponding switchboard terminal, and means for causing the release of said switches, the release of the switch at the 100 sub-office being controlled over one of the 105 talking conductors of said trunk.

15. In a telephone system, a central office and a sub-office; a group of subscribers' lines terminating at said sub-office; a switchboard having a plurality of subscribers' line terminals at said central office; a plurality of trunk lines, less in number than the subscribers' lines or corresponding switchboard 110

- terminals, said trunk lines being adapted to form connecting links in the talking circuits between the subscribers' lines and the central office, a selecting switch at each end of each trunk line; means for appropriating an idle one of said trunk lines upon the establishment of an outgoing connection with a switchboard terminal at the central office; means for causing the simultaneous 10 operation of the two switches of said trunk to connect respectively at one end with the switchboard terminal so connected with, and at the other end with the corresponding subscriber's line; and means for causing the 15 release of said switches, the control between said switches for both selecting and releasing being over the talking circuit wires of said trunk line.
16. In a telephone system, a central office 20 and a sub-office; a group of subscribers' lines terminating at said sub-office; a switchboard having a plurality of subscribers' line terminals at said central office; a plurality of trunk lines, less in number than the sub- 25 scribes' lines or corresponding switchboard terminals, said trunk lines being adapted to form connecting links in the talking circuits between the subscribers' lines and the central office; a selecting switch at each end of each 30 trunk line; means for appropriating an idle one of said trunk lines upon the establishment of an outgoing connection with a switchboard terminal at the central office; means for causing the simultaneous opera- 35 tion of the two switches of said trunk to connect respectively at one end with the switchboard terminal so connected with, and at the other end with the corresponding subscriber's line; and means for causing the 40 release of said switches at the end of a conversation, the release of the switch at the sub-office being controlled over one of the talking conductors of said trunk.
17. In a telephone system, a central office and a sub-office; a group of subscribers' lines terminating at said sub-office; a group of trunks common to said group of subscribers' lines, but less in number than said subscribers' lines extending between said offices; a switch for each of said trunks at said sub- 45 office; means for appropriating an idle one of said trunk lines upon the initiation of a call on one of said lines; means for causing the operation of the switch of an appropriated trunk to connect said trunk with 50 said line, and means for releasing the switch of said trunk, said latter means being controlled at said central office over one of the talking wires of said trunk.
18. In a telephone system, a central office 60 and a sub-office; a group of subscribers' lines terminating at said sub-office; a group of two-wire trunks common to said group of subscribers' lines, but less in number than said subscribers' lines extending between 65 said offices; a switch for each of said trunks at said sub-office; means for appropriating an idle one of said trunk lines upon the initiation of a call on one of said lines; means for causing the operation of said switch of 70 an appropriated trunk to connect said trunk with said line, and a release relay at said sub-office, said relay being controlled over one of the wires of said trunk.

Signed by me at Chicago, county of Cook 75 and State of Illinois, in the presence of two witnesses.

EDGAR H. CLARK.
